Attorneys

UNITED STATES PATENT OFFICE.

IRA CLAY WHITE, OF BROWNSVILLE, ARKANSAS.

POULTRY ROOST.

Application filed June 7, 1923. Serial No. 643,989.

This invention relates to roosts or perches for poultry.

The object of the invention is to provide a roost of this character which is readily removable for cleaning and other purposes and which is collapsible to facilitate handling thereof.

Another object is to provide a roost of this character which includes a number of perch poles equipped with germicide containers to rid the fowls roosting thereon from mites, lice and the like.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a plan view of a roost constructed in accordance with this invention.

Fig. 2 is a side elevation thereof, and

Fig. 3 is a transverse section taken on the line 3—3 of Fig. 1, looking in the direction of the arrows.

The roost constituting this invention comprises two sections, 1 and 2 arranged in longitudinal alignment and hingedly connected at their inner ends by a pintle 3 which extends loosely through the lapping ends 5 of a plurality of longitudinal bars 4 forming a hinged connection between the sections. As shown the outer bar 4 of one section at one side is located outside that of the other section while at the opposite side the arrangement is reversed (see Fig. 1) to provide for one section folding snugly within the other when the roost is collapsed.

Each section is composed of a plurality of laterally spaced longitudinally extending bars 4, three of which are here shown, and which are connected by longitudinally spaced cross bars 6 which constitute the perches. These perches 6 are preferably secured to the bars 4 by screws 7 to adapt them to be taken apart when desired. The perches

6 are also provided in their upper faces with a plurality of germicide containers in the form of pockets 8, so that the poultry roosting on these perches will be freed from mites and the like by the fumes of the germicide in the pockets rising up and passing into the feathers of the fowl.

This roost is equipped at the side edges thereof preferably near the corners, with hangers 9, four of which are here shown, two carried by each section. These hangers 9 are made hook-shaped and are designed to engage their supports, not shown, fastened to the walls of the hen house. These supports are preferably in the form of side pieces or bars and when the hangers 9 are hooked over them, the projecting ends of the perches 6 will also rest on these side pieces and prevent collapsing of the roost. Spacing blocks 10 are arranged at diametrically opposite corners between the bars 4 and the support engaging hooks of the hangers 9 so that the hooks of one section will align longitudinally with those of the other to properly position them relatively to their supports. When it is desired to remove the roost for any purpose, the hangers 9 are disengaged from their supports and the roost folded at the center to facilitate handling. This hinged connection of the sections also adapts the roost to occupy a small space when storing or packing it for shipping. Fastening elements in the form of cotter-pins 11 are arranged transversely through the pintles 3 adjacent the inner faces of the inner side bars as is shown clearly in Fig. 1 and which are removable to facilitate separation of the sections when desired for cleaning or other purposes.

While six perch bars only are shown, obviously any desired number may be employed and the sections 1 and 2 may be made of any desired size to fit the poultry house in which they are to be used.

I claim:—

In a roost, a pair of sections, each of the sections including longitudinally extended outer bars and inner bars arranged in spaced relation with each other, spaced cross bars having their ends extended beyond the outer longitudinal bars to provide supports for

the roost, hangers on the roost, the first mentioned bars having aligning openings, a pin-
tle extending through the aligning openings
to removably connect the sections, removable
members extending through the pintles ad-
jacent to the outer longitudinal bars to re-
strict movement of the sections over the pin-

tle, and said cross bars having openings de-
fining cups.

In testimony that I claim the foregoing ¹⁰
as my own, I have hereto affixed my signa-
ture.

IRA CLAY WHITE.
